(57) **CLAIM**

The ornamental design of a foot plate for a diving fin, as shown.

DESCRIPTION

FIG. 1 is a front perspective view of a foot plate for a diving fin in accordance with the present invention;

FIG. 2 is a rear perspective view thereof;

FIG. 3 is a top plan view thereof;

FIG. 4 is a bottom plan view thereof;

FIG. 5 is a right side plan view thereof;

FIG. 6 is a left side plan view thereof;

FIG. 7 is a front plan view thereof; and,

FIG. 8 is a rear plan view thereof.

The broken lines are for environmental purposes only and form no part of the claimed design.
